UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,417,115.

Specification of Letters Patent. Patented May 23, 1922.

Application filed September 10, 1919. Serial No. 322,830.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it applies to make and use the same.

This invention relates to improvements in staybolt structures for boilers,—one object of the invention being to provide a bearing member for the head of a staybolt, having a universally movable mounting in a boiler sheet whereby accurate alignment of the staybolt may be insured before the bearing member is made rigid with the boiler sheet and provide a simple and efficient closure for the bearing member which may be seated on the latter and made permanently rigid with the same.

With this and other objects in view, the invention consists in certain novel features of construction and combinations of parts as hereinafter set forth and pointed out in the claims.

The accompanying drawing is a sectional view showing an embodiment of our invention.

1 represents a boiler sheet provided with an opening 2, the major portion of the wall 35 of which is curved or rounded as indicated at 3. The curved wall 3 serves as a seat for the curved or rounded portion 4 of a bearing sleeve or member 5, the latter having an interior curved seat 6 for the rounded head 7 of a staybolt 8.

By mounting the bearing sleeve in the opening in the boiler sheet so that it may be capable of universal movement, said sleeve can be so adjusted as to insure accurate alignment of the staybolt with its points of connection with the respective boiler sheets, and when said sleeve shall have been made to assume such adjustment, it will be fixedly united to the boiler sheet by a weld 9. This weld surrounds the sleeve near where the latter enters the opening in the boiler sheet and effects a union which will, in effect,

make the sleeve integral with the boiler sheet.

The bearing sleeve has such dimensions 55 as to provide a clearance space 10 for the bolt head between the latter and a closure 11 on said sleeve.

The closure 11 is made in the form of a plate which may be concavo-convex and it is 60 seated on the end face 12 of the sleeve. To insure proper centering of the closure, it may be made with a shoulder 13 which may enter the end portion of the sleeve.

The diameter of the plate or closure 11 is 65 appreciably less than the outside diameter of the outer end of the sleeve, and the space between the peripheral face of the closure and the peripheral edge of the end of the sleeve is occupied by a weld 14 which serves 70 to permanently unite said closure to the sleeve and make it, in effect, an integral part of the same.

In order to permit the testing of the bolt, the head of which is sealed within the bearing sleeve or member, said bolt will be provided with a tell-tale hole 15 which may extend from the inner end of the bolt and terminate at its outer end within the headed end thereof.

Having fully described our invention what we claim as new and desire to secure by Letters-Patent, is:—

1. The combination with a boiler sheet having an opening, of a bearing member 85 having initial universal mounting on the wall of said opening and permanently sealed to the boiler sheet, said bearing member permanently closed at its outer end, and a staybolt having a headed end mounted in said 90 bearing member and having a tell-tale-hole extending from within said headed end to the other end of the bolt.

2. In a staybolt structure, the combination with a boiler sheet having an opening 95 therein, a bearing member mounted at said opening and sealed to the boiler sheet, and a staybolt having a head mounted in said bearing member, of a closure seated upon the end face of said bearing member, and a weld 100 uniting the peripheral face of said closure to the end face of the bearing member.

3. In a staybolt structure, the combination with a boiler sheet having an opening

therein, of a bearing member having initial universally movable mounting in said opening, a weld uniting said bearing member to the boiler sheet, a staybolt having a head mounted in said bearing member, a plate closure seated on the end face of the bearing member, and a weld uniting the peripheral portion of the plate closure to said end face.

In testimony whereof, we have signed this specification in the presence of a subscribing witness.

BENJAMIN E. D. STAFFORD.
ETHAN I. DODDS.

Witness:

EDWIN S. RYCE.
